UNITED STATES PATENT OFFICE.

FRANK ARMSTRONG AND NATHANIEL W. VANDEGRIFT, OF BRIDGEPORT,
CONNECTICUT.

WRENCH.

SPECIFICATION forming part of Letters Patent No. 392,300, dated November 6, 1888.

Application filed October 15, 1887. Serial No. 252,457. (No model.)

To all whom it may concern:

Be it known that we, FRANK ARMSTRONG and NATHANIEL W. VANDEGRIFT, citizens of the United States, residing at Bridgeport, 5 Fairfield county, Connecticut, have invented new and useful Improvements in Wrenches, of which the following is a specification.

This invention relates to certain new and useful improvements in wrenches; and it consists 10 substantially in such features of construction, arrangement, and combinations of parts as will hereinafter be more particularly described, and pointed out in the claims.

On the 6th day of May, 1884, Letters Patent 15 No. 298,043 were granted to Nathaniel W. Vandegrift for improvements in wrenches, and wherein the main features employed are a hollow frame or sleeve, through which passes a sliding jaw operated by a hand-nut, and a pivoted jaw having its bearing or fulcrum between lugs projecting from said hollow frame or sleeve at its forward end. By examining the Letters Patent referred to it will be seen that the shank of the sliding jaw is screw-threaded for its entire length, and that, due to the location of the nut by which said jaw is operated, the said shank has a comparatively small or limited bearing between the walls of the sleeve within which it works. It will further be seen that 20 in the use of this wrench all lateral as well as vertical strain is necessarily received by the shank of the sliding jaw at whatever point said jaw be brought or adjusted. By practical test and experience with this wrench it has been found that in a very short time the continued strain on the shank so twists or distorts the threads thereon as to finally render it impossible to adjust the jaw to suit varying sizes of work, and consequently the wrench is 25 thereby rendered useless.

In our invention, in order to overcome the disadvantages or defects above mentioned, we change the location of the adjusting-nut to or near the rear end of the hollow frame or sleeve, 45 thereby furnishing a greater superficial area or bearing-surface for the shank of the sliding jaw, and for a distance about equal to the length of said solid portion of the frame or sleeve we form the shank of the sliding jaw of

a solid portion having a perfectly smooth or unbroken surface, while for the remainder of length of said shank the screw is formed by which adjustment may be effected by operating the hand-nut. From this construction it will be seen that by virtue of the bearing between the opposing surfaces of the solid portion of the shank and the walls of the sleeve all strain will be distributed in a direction parallel to the axis of the screw, and that no portion of the screw being in contact with the walls of the sleeve or exposed beyond either end thereof, whether the jaw be adjusted in or out, the same is relieved from all lateral strain.

Referring to the accompanying drawings, Figure 1 represents a side view of a wrench 65 embodying our invention, and Fig. 2 is a longitudinal sectional view thereof.

Reference being had to the several parts by the letters marked thereon, A represents the hollow sleeve or frame having an opening in 70 its sides at or near the rear end thereof, in which opening the hand-nut B is accommodated, and the rear end of said sleeve is screw-threaded interiorly for a short distance, by which to adapt it to receive the hollow handle 75 C. The entire portion of the sleeve forward of the opening a therein is solid, and it will be seen that the outer side of the same at the top is formed or provided with lugs b, between which is pivotally held the jaw D. Moving 80 upon the said jaw D is a sliding jaw, E, the shank of which is formed with a square portion, c, and a screw-threaded portion, d, the said shank working within the sleeve, as shown, with the screw-threaded portion there- 85 of passing through the hand-nut, and it is evident that on operating this hand-nut the sliding jaw will be moved in a direction corresponding to that in which the nut is rotated. As before remarked, no portion of the screw is 90 ever in contact with the walls of the sleeve in which the shank of the sliding jaw works, and by virtue of the solid portion receiving all strain the same will be induced to take a direction parallel to the axis of the screw, and 95 consequently the threads thereof will not be twisted or distorted, as is the case with the Letters Patent hereinbefore referred to.

Having thus described our invention, what we claim as new, and desire to secure by Letters Patent, is—

1. A wrench constructed of a hollow sleeve or frame, a pivoted jaw, and a sliding jaw working in the sleeve, the shank of which is formed of a smooth or unbroken portion and a screw-threaded portion, substantially as described.

2. In a wrench, the combination, with a hollow sleeve or frame having an opening in its walls at or near its rear end for the accommodation of a hand-nut, and a jaw pivoted thereto at or near its forward end, of the sliding jaw

moving in said sleeve, the shank of which is formed of a smooth portion, *c*, and a screw-threaded portion, *d*, the latter being provided with a hand-nut, substantially as described.

In testimony whereof we have hereunto set our hands in the presence of two subscribing witnesses.

FRANK ARMSTRONG.

NATHANIEL W. VANDEGRIFT.
